(57) **CLAIM**

The ornamental design for a biosample processing cartridge, as shown and described.

DESCRIPTION

FIG. 1 is a perspective view of a biosample processing cartridge showing our new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is a perspective view showing the use status of the biosample processing cartridge.

The broken lines in FIGS. 1-10 and the areas within them depict portions of the biosample processing cartridge that form no part of the claimed design. The article in broken lines in FIG. 10 enclosing the biosample processing cartridge is environmental subject matter that forms no part of the claimed design. The dot dash dot broken lines in FIGS. 3 and 9 depict the boundary of the claim and form no part thereof.
